[57] **CLAIM**

The ornamental design for an umbrella handle, as described
and shown in the drawings.

DESCRIPTION

FIG. 1 is a side elevation of the umbrella handle;

FIG. 2 is a front elevation of the umbrella handle shown in
FIG. 1;

FIG. 3 is a top plan view of the umbrella handle shown in
FIG. 1;

FIG. 4 is a bottom plan view of the umbrella handle shown
in FIG. 1;

FIG. 5 is an enlarged sectional view taken along the line
5—5 in FIG. 3;

FIG. 6 is a side elevation view of the umbrella handle shown
in use; and,

FIG. 7 is a side view of the umbrella handle shown in use.
The broken line showing of environment in FIGS. 6 and 7
is for illustrative purposes only and forms no part of the
claimed design.
